METHOD OF AND MEANS FOR PROPELLING SHIPS

Application filed April 13, 1928. Serial No. 269,668.

It is well known that ships ordinarily are propelled by paddle wheels or by screw propellers. The screw propeller method is the most common and is attended with many disadvantages of which the following are the most important. The over-all efficiency expressed in ratio of tow rope power to indicated engine room power, is seldom greater than fifty per cent. The driving mechanism, if direct, is large and heavy. If high speed turbines are used as a source of power, mechanical and electrical speed reducing means are required in transmitting this power to the necessarily relatively slow revolving propellers.

Furthermore, it is known that ships like any other object forced through water, moving at high speeds produce waves which increase the pressure or resistance on the bow 20 of the ship and impede movement thereof. Such waves travel at the speed of the ship, and at distances from crest to crest which increase rapidly with the speed from approximately eighty feet at twelve knots to 25 five hundred feet at thirty knots.

Calculations show that a pressure equal to six inches of water head at the stern of a cargo boat in excess of the pressure at the bow is sufficient to drive such boat at its 30 usual speed of ten to twelve knots per hour, while in the case of large high speed passenger ships, like the *Mauritania*, a difference in pressure equal to a head of three feet of water or even more would be required.

One object of my invention is to provide a novel and improved method of ship propulsion consisting in creating such a difference between the pressures of the water at the bow and the stern of a ship and utilizing said 40 pressure difference for propelling the ship thereby eliminating the above-mentioned disadvantages of screw-propeller propulsion.

Another object is to provide a method of 45 propelling ships which consists in producing a pressure wave at a point in advance of the bow of the ship so that the ship may take entrance in the trough following such pressure wave. It is evident at once, that if 50 the ship takes its entire entrance in the

trough following said pressure wave, it will by reason of its pressure of entrance create another wave which will counteract on the previous pressure wave. It is necessary, therefore, to produce a pressure wave of sufficient magnitude that after a part of its trough has been neutralized by the wave of entrance of the ship, there remains enough trough to balance the skin friction of the ship and stern cavitation. 55

Another object is to provide novel and improved means for reducing the hydrostatic pressure at the bow of a ship. 60

Other objects are to provide novel and improved means for producing such pressure waves in advance of the ship's bow; to provide such means whereby the distance ahead of the bow at which such pressure waves are produced may be varied; to provide a method of ship propulsion consisting in imparting 70 energy to the water at a point in advance of the stern or exit portions of a ship's hull to increase the hydrostatic pressure or head at the stern; to provide means for so imparting energy to the water ahead of the exit portions 75 of a ship's hull, and to obtain other advantages and results as will be brought out by the following description.

In the accompanying drawings I have schematically illustrated my method of and 80 means for propelling ships, but it should be understood that this is primarily for explaining the principles of the invention and that many modifications thereof may be made by those skilled in the art without departing 85 from the spirit or scope of the invention.

Referring to said drawings in which corresponding and like parts are designated throughout the several views by the same 90 reference characters,

Figure 1 is a schematic plan view of a ship's hull showing the principles of one form of my method and means;

Figure 2 is a longitudinal sectional view 95 taken on the line 2-2 of Figure 1;

Figure 3 is a plan view of a modified form of the invention; and

Figure 4 is a similar view of a further modification.

Specifically describing the form of the in- 100

vention shown in Figures 1 and 2, the reference character 1 designates the hull of a ship having sides of entrance 2, 2 and a projection 3, a pipe in the form shown extending 5 forwardly from the bow below the normal water level 4, and formed with a downwardly directed opening 5. This pipe is connected at 6 to any suitable source of compressed air. In operation initially slow motion is imparted 10 to the hull in any suitable manner as by a screw propeller, and compressed air is ejected in a continuous stream from the opening 5. This creates a pressure wave 7, 7 at each side of the hull and at a point ahead of the 15 bow and following troughs 8, 8 which extends throughout the length of the entrance sides 2, 2. The ship therefore takes its entrance in said trough the surface of the water in which is so low that only slight impedance by the 20 water to forward movement of the ship is produced. The resistance by the water to movement of the ship is thus materially less than it would be according to known practice. This pressure wave gradually flattens out or 25 decreases in height as shown by dotted lines 9 and 10, and as the ship travels forwardly is influenced forwardly by the pressure of the wave on the stern 11 as indicated at 12.

The invention may be utilized as an auxiliary to ordinary screw propeller propulsion, the reduction in hydrostatic pressure at the bow caused by the air emitted from opening 5 decreasing the resistance by the water to the force exerted by the propeller; but the air 25 may be ejected from the opening 5 in such volume and at such pressure that the pressure wave when the stern reaches it as at 12, has sufficient head in excess of the pressure at the bow to exert a propelling force on the ship.

40 In Figure 2, I have shown further means to increase the energy in the wave just before the stern reaches it, said means comprising an opening 13 in the ship's hull connected to the air supply pipe 6. By this means the height 45 or pressure head of the wave at point 14 is increased and the pressure thereof imparted to the stern at 12. If this increase in pressure head is only slight, it will serve only to reduce the retarding effects on the hull of stern cavitation, but the pressure may be so great as to 50 exert a propelling force on the stern and drive the ship. The distance between the openings 5 and 13 must be so correlated to the length and the speed of travel of the ship, that the 55 air pressure will be applied at the proper point 14.

It may be desirable to provide means for varying the distance ahead of the entrance surfaces 2, 2 at which the pressure wave 7 60 is produced so that the pressure wave is located in advance of the hull of the ship a distance proportional to the square of the speed of travel of the hull which will vary at different times, and for this purpose I may 65 make the pipe 3 slidably adjustable through

the bow, or the projection may be made integral with the hull and the opening 5 formed at different distances from the entrance surfaces 2, 2, as shown in Figure 3, or a plurality of openings any one of which may be used, can be provided.

70 It is also possible to provide for the hull taking entrance in a plurality of stages, as shown in Figure 4, where two projections 15 and 16 of different widths connected by entrance surfaces 17, 17 are provided. The projections 15 and 16 have respective openings 18 and 19 to eject compressed air. The pressure wave 20, produced by the air from opening 19 is partially neutralized by the first 80 stage of entrance taking by the surfaces 17, 17, and the pressure of said wave is then increased by the air from opening 18 to form a trough in which the second stage of entrance is taken by the surfaces 2, 2.

85 I do not desire to be understood as limiting myself to the precise form of taking entrance illustrated, as it is possible to make the bow of the hull shallow and take entrance in the direction of draft only in the 90 wave troughs.

95 By moving the openings 5, 13, 18 and 19 forwardly or astern, I may compensate for the changes in wave length i. e., distance between the crests of the wave, which varies with the speed of the ship. As before mentioned, a small direct propelling force such as may be provided with a screw propeller, is required to produce a low initial speed, and the invention may be used only to reduce the 100 hydrostatic head at the bow whereby less power from a screw propeller is required, or a sufficient difference in pressure at bow and stern may be produced to propel the ship 105 after it has once been started by other means.

I do not wish to be limited to the use of compressed air for creating the above-mentioned pressure waves. I may for instance discharge a mixture of air and gas or air and oil vapor in the form of a succession of huge bubbles and explode these bubbles immediately after their emission, thereby creating a series of closely spaced points or zones of pressure. Such a succession of zones of 110 pressure will give substantially the same effect as the jet of air.

115 Having thus described my invention, what I claim is:

1. A ship's hull having a forward projection from its bow submerged in the water, 120 and means carried by said projection to produce a pressure wave in advance of the bow, and means for adjusting the last-named means to vary the distance between the crest of said wave and the bow of the hull.

125 2. A ship's hull having a forward projection from its bow submerged in the water and exit surfaces, means carried by said projection to produce a pressure wave in advance 130 of the bow, means for imparting energy to the

water ahead of said exit portions to increase the hydrostatic pressure on said exit portions, and means for adjusting said means relative to each other and the ship in accordance with
5 the speed of travel of the ship.

3. A ship's hull having entrance surfaces, and means for producing a pressure wave at a point ahead of said entrance surfaces of said hull a distance proportional to the square
10 of the speed of said hull so that said entrance surfaces take entrance in the trough following said pressure wave.

4. The method of propelling ships consisting in establishing a pressure wave at a point
15 ahead of the hull and adjusting the distance of said wave in advance of the hull in proportion to the square of the speed of travel of the hull.
